UNITED STATES PATENT OFFICE.

HARVEY S. SPRAGUE, OF DANA, INDIANA.

PISTON-VALVE.

No. 901,846.

Specification of Letters Patent.

Patented Oct. 20, 1908.

Application filed February 12, 1907. Serial No. 357,071.

To all whom it may concern:

Be it known that I, HARVEY S. SPRAGUE, a citizen of the United States, residing at Dana, in the county of Vermilion and State 5 of Indiana, have invented certain new and useful Improvements in Piston-Valves, of which the following is a specification.

My invention relates to improvements in steam-engine valves, more especially the 10 slide-type. Its objects are principally to provide for the freely moving action of the valve; to readily supply and exhaust the steam by the valve-action; to allow the passage of the steam practically entirely around 15 the valve for expediting its delivery to the valve; to readily compensate for the wear of the valve; to relieve excess of steam-pressure in the valve-chamber; to provide for the freely working action of the valve as relates 20 to its stem; to facilitate the lubrication of the valve; and to carry out these objects in a simple, ready and effective manner.

Said invention consists of certain features or instrumentalities substantially as herein- 25 after fully disclosed and specifically pointed out by the claims.

In the accompanying drawings illustrating the preferred embodiment of my invention—Figure 1 is a vertical longitudinal section 30 thereof. Fig. 2 is a transverse section of the same. Fig. 3 is a like view upon an enlarged scale of the valve chamber casing or housing removed. Fig. 4 is a detached partially side view and partially sectional view of the valve, with its stem partly broken away. Fig. 5 is an end view of the same. Fig. 6 is an end elevation of the valve casing or housing, showing more particularly one of its relief valves. Fig. 7 is an enlarged 40 broken detailed sectional view also disclosing more especially one of the latter.

In the disclosure of my invention, I suitably mount upon each cylinder 1 of a steam-engine, within the steam-chest 2, a casing or 45 inclosure 3 forming a chamber for, and containing a cylindric or piston-form of valve 4. Said valve casing or chamber is adjusted and held in position by screw-bolts 5, inserted through the upper portion of the 50 steam-chest 2 and binding upon said valve-casing, and by like screw-bolts 6 screwing into the ends of said casing and adapted by suitably manipulating the same to permit of bringing their heads into engagement with 55 the opposite portions of the steam-chests, as is apparent.

The valve 4 preferably cylindric in general outline as above noted, has two end-enlargements or faces 5^a which have inserted thereinto series of split rings or packing 6' whereby wear may be compensated as well as providing for packing purposes. The outer-end rings are extended clear to, and stand flush with the end-walls of the valve or piston for sharply defining the wall-edges 65 and consequently promoting the passages of the steam to the ports delivering into the engine-cylinder. The wear-compensating and packing action of the rings 6' are due to their measurably resilient character and 70 to being split, the same being severed diagonally through their transverse areas as disclosed. Said piston or valve is centrally contracted, providing thereby a circular exhaust steam passage 7 effective, according to 75 the position of the valve, for establishing communication between either of the ports 8 and the exhaust-port 9, when the other port 8 is shut off from said exhaust-passage 7 and is taking live steam from the steam-chest and delivering it into the engine-cylinder, as well understood in this art. Said piston-valve has its stem 10 extending through a longitudinal passage therein 80 which is somewhat greater in cross-section 85 than said stem to permit of the requisite working or play of the valve or the differential movement therebetween as is clearly appreciated. Said stem has a nut 11 and a washer 12 applied to its screw-threaded end 90 13, the valve 4 having in its ends countersink-like recesses 14, one recess receiving said nut and washer and the other recess receiving a washer 15 inserted upon said stem, and effective to engage that end of the 95 valve. Said stem is also diametrically reduced to form a shoulder 16 for engagement with said washer 15 for the retention of the valve in place as against endwise displacement, and yet does not interfere with the otherwise limited movement or play of the valve upon its stem as above described.

The valve-casing 3 has formed in its walls, beyond, but communicating with the chamber receiving the valve 4, series of arcuate steam passages 16, 17 merging into ports 18, 19 in its base corresponding with, and opposed to the live-steam supply and exhaust ports of the engine-cylinder, as shown, for receiving and permitting the delivery of the 110 steam through said passages 16, 17 whereby said steam is caused to encompass and

5 cushion the valve, thus providing for effectively balancing the latter and accordingly rendering it freely moving and greatly aiding its working action, as is apparent. The
5 steam-passages 16, 17, are formed in the chamber of the outer valve-casing by means of vertical transverse partitions *a* integral, of course, with said casing and which partitions have circular openings *b* therein co-
10 inciding with the corresponding openings in the ends of said casing receiving the piston-valve, the edges or walls of said openings thus forming seats for said valve and whereby the steam is allowed to pass through said
15 passages and laterally of said valve and said seats, as in effecting the balancing of said valve.

17 In order to relieve excess of steam-pressure in the valve-chamber, automatically operating valves 20 are suitably seated and arranged in the heads or ends of the valve-casing whose stems are supported in brackets 21 fixed to said casing and to which stems are applied springs 22 whose tension is effective to retain the valves closed except when exerted upon beyond a predetermined pressure as will be readily appreciated. These valves are each formed preferably of a disk or plate 23 covering a port in each 30 head or end of the valve-casing, said plate or disk having projecting from one side thereof guiding arms 24 "turn-stile" like in formation and in a single casting for controlling the movement of the valve.

35 It is remarked that I have produced a steam-engine valve of the balanced slide type, which is characterized for great simplicity; which is quickly responsive in action to the steam pressure; for being effectively balanced and attended with the minimum amount of friction in movement; and is applicable generally for use without any appreciable or material changes to valve or engine-cylinder while the valve is relatively 40 inexpensive and readily accommodated to all conditions necessary for its adoption.

45 It will be further noted that my invention,

50 may, as just stated, be employed in connection with engines as now in use without requiring any remodeling or changes of any character whatever, thus saving the expense attending the making of new patterns, casting new cylinders and chests in order to provide for the use of a balanced valve as, so far as my experience extends, is necessary in 55 applying all other valves of like character. It is still further observed that by means of my valve the cylinder will be relieved of all water should the engine be started with water in the cylinder, or subsequently enter 60 the latter, the engine priming or foaming over, thus avoiding what might otherwise result in the bursting of the cylinder, or blowing out of its heads.

65

I claim—

1. A slide valve comprising a casing having a valve chamber formed therein, a piston valve received therein, and the said casing having steam passages formed therein, and openings leading from the steam passages to 70 the valve chamber for admitting steam for cushioning the valve, and spring controlled relief valves received in the heads of the casing.

2. A steam-engine slide-valve of the piston-type, comprising a casing therefor, a chest inclosing said casing, and spring-controlled relief valves arranged in the heads or ends of said casing.

3. A steam valve of the piston type, comprising a valve-casing having a disk-shaped relief-valve arranged on the end of said casing and having projecting from one side thereof guiding arms for controlling the movement of the valve, said valve having a 85 spring arranged in connection therewith for its retention in initial position.

In testimony whereof I affix my signature, in presence of two witnesses.

HARVEY S. SPRAGUE.
